UNITED STATES PATENT OFFICE.

ANNA SCHWOLL, OF LEIPSIC, OHIO.

STOVEPIPE-DAMPER.

No. 833,554.

Specification of Letters Patent.

Patented Oct. 16, 1906.

Application filed February 8, 1906. Serial No. 300,066.

To all whom it may concern.

Be it known that I, ANNA SCHWOLL, a citizen of the United States, and a resident of Leipsic, in the county of Putnam and State of Ohio, have invented a new and useful Improvement in Stovepipe-Dampers, of which the following is a specification.

My invention relates to a stovepipe-damper, and has for its object to provide a simple, inexpensive, and reliable device of the kind that is easily mounted in a pipe and that is readily adjusted to desired positions to regulate the draft and secured in such position by means which indicate the degree of opening. I accomplish these objects by constructing a damper as hereinafter described, and illustrated in the drawings, in which—

Figure 1 is a bottom view of my invention mounted in a stovepipe; and Fig. 2 is a longitudinal section of a stovepipe equipped with my invention, the section being in a plane of the axis of the pipe.

In the drawings, 1 represents a stovepipe, and A a damper, constructed in accordance with my invention, pivotally mounted in the pipe.

The damper A comprises the semicircular leaves 2 and 3 of equal radius and provided, respectively, with the complementary knuckles 4 and 5, which when the leaves are diametrically abutted and extended oppositely in the same plane extend in axial alinement diametric of the complete circle formed by the two leaves, the circle having a diameter slightly less than the inner diameter of the stovepipe 1, and a pintle 6, which extends through the knuckles of the leaves and has end portions which extend through suitable orifices in the stovepipe 1 at diametric opposite points, one of which end portions is provided with a fixed head 7 and the other with a head 7', which is detachably threaded thereon. The leaves 2 and 3 thus mounted on the pintle 6 are each free to rotate thereon independently of the other as the leaves of a hinge.

To the bottom face of the leaf 2 is secured one end portion 8 of an arm-plate 9, which extends by a bend 10 over the knuckle 4 of the plate 2 and has a free end portion 11 extending in the same plane with the end portion 8, the end portions 8 and 11 of the arm 9 being in a plane coinciding with the plane of the leaf 2, the end portion 11 being adapted

to engage the leaf 3 when the leaf 3 is extended in the same plane as the leaf 2. 55

The leaf 2 is provided with a suitable orifice in which is secured by a nut 12 an eye-bolt 12', to which is linked one end of a connecting-rod 13, the opposite end of which is pivotally connected to an operating-rod 14, which extends through a suitable orifice in the wall of the stovepipe and through a thimble 15, suitably secured to the wall of the pipe around the orifice, the outer end portion of the rod 14 being threaded and provided with a suitable knob 16, internally threaded to run thereon, and the inner end with the shoulder 17, which respectively form stops for the inward and outward movement of the rod through the thimble. The thimble 15 is located in a horizontal plane above the horizontal plane of the pintle-rod 6, and the rod 14 moves in a line that is diametric of the stovepipe and parallel with a line at right angles to the pintle and diametric of the stovepipe. The rod 14 is of such length between the shoulder 17 and the knob 16 that when the rod 14 is pulled outward until the shoulder 17 is engaged with the pipe 1 the connecting-rod 13 has raised the leaf 2 to a vertical position and when the rod is pushed inward until the knob 16 engages the outer end of the thimble 15 the leaf 2 is pushed downward through an arc of 75 80 85 ninety degrees to a horizontal position.

Intermediate between the shoulder 17 and the knob 16 the rod 14 is provided at intervals of its upper circumference with the transverse shallow U-shape incuts or notches 90 18, which incuts are adapted to register with an opening in the top of the thimble adapted to receive a ball 20, which is secured therein by a spring 21. The incuts 18 are formed at such regular intervals of the rod 14 as indicate a definite degree of movement of the leaf 2 from a horizontal position to a vertical, so that it may be known when the ball 20 has dropped into any notch to what degree the leaf 2 is opened from the horizontal by the 95 100 number of notches outside the thimble and also the degree of opening of the leaf 3, since as the leaf 2 is raised leaf 3 will open by gravity, as permitted by the arm 9, and as leaf 2 is lowered toward a horizontal position the 105 arm 9 will raise the leaf 3 an equal number of degrees toward a horizontal position. When the ball 20 is engaged with a notch of the rod

14, it frictionally locks the rod against movement inward or outward by the weight of the leaves 2 or 3; but a slight push or pull on the knob 16 is sufficient to raise the ball out of the 5 notch against the pressure of the spring 21.

A damper thus constructed is readily assembled in position in a section of stovepipe by first placing the top side of leaf 3 on the top side of leaf 2, with the knuckles 5 of leaf 3 10 alined with the knuckle 4 of the leaf 2, and then inserting the leaves thus conjoined into the pipe and alining the knuckles with the opposite pintle-orifices, which is more conveniently done than with a solid disk 15 damper. The knuckles being thus alined with the pintle - orifices, the pintle - rod is readily inserted, and, the head 7' being run on the threaded end of the pintle-rod, it is firmly secured diametric of the pipe, with the 20 leaves rotatably mounted thereon, after which the leaf 3 is turned over into engagement with the arm 9. To mount the adjusting-rod 14 in the thimble, the knob 16 is removed from the end of the rod, and the 25 threaded end is inserted outward through the inner end of the thimble, and the knob being again attached the rod is pulled outward, and the eyebolt 12' is then inserted through the leaf 2 and secured thereto by the nut 12, 30 run in the end of the eyebolt, which completes the attachment of the damper in position for use.

Preferably the leaves 2 and 3 are provided with a suitable number of draft-orifices 22, 35 which provide the minimum of draft.

I am aware that disk dampers diametrically mounted on a pintle-rod which is journaled in the pipe and provided with a knob or handle for turning the damper is in com-

mon use; but dampers so constructed are 40 more difficult to mount in a pipe, and when mounted soon become loose on the pintle, and thereafter their operation becomes uncertain and unreliable. By constructing a damper in accordance with my invention as shown and 45 described it is readily attached to a pipe, its adjustment is made positive, and its exact position is indicated.

What I claim to be new is—

The combination with a vertically - dis- 50 posed stovepipe, of a pintle-rod secured diametric of the pipe, a pair of semicircular leaves of equal radii rotatably and independently mounted on the pintle by complementary knuckles formed on the leaves, and 55 alined diametric of the circle of the leaves, an arm secured to one side of one leaf and adapted to engage the corresponding side of the other leaf, when the leaves are extended opposite in a common plane, means connected 60 to one leaf comprising a pivotally-jointed rod extending into the pipe and adapted to move the leaf upward and downward through an arc from a horizontal to a vertical plane and return, the other leaf being oppositely 65 moved through a diametrically opposite arc in one direction by gravity, and in the opposite direction by the arm, and means to yieldingly lock the rod at definite degrees of movement of the leaf through the arc, sub- 70 stantially as set forth.

In witness whereof I have hereunto signed my name, in the presence of two subscribing witnesses, this 31st day of January, 1906.

ANNA SCHWOLL.

In presence of—

GEORGE P. GREENHALGH,
CHAS. A. BOOKE.
